UNITED STATES PATENT OFFICE.

FREDERICK WOHN, OF SAN ANTONIO, TEXAS.

OVERHEAD RADIAL CONVEYER SYSTEM.

1,391,598.

Specification of Letters Patent. Patented Sept. 20, 1921.

Application filed December 6, 1920. Serial No. 428,535.

To all whom it may concern:

Be it known that I, FREDERICK WOHN, a citizen of the United States, residing at San Antonio, in the county of Bexar and 5 State of Texas, have invented a certain new and useful Improvement in Overhead Radial Conveyer Systems, of which the following is a specification.

This invention relates to an apparatus or 10 system for handling freight or merchandise in transportation for storing the same in warehouses and the like; or for transferring the same from freight cars to vessels or vice versa.

15 The object of the invention is to provide an apparatus or system for handling freight or merchandise and moving the same from place to place, which will avoid the necessity of employing a large number 20 of men or stevedores with the usual hand trucks, as is customary in the handling and moving of freight or cargoes from place to place, as from cars to warehouses or from cars to vessels or from vessels to cars, as the 25 case may be.

The invention consists in an overhead radial conveyer system including a crane supported to swing about a center upon an overhead circular track or tracks, and adapted 30 to support a traveling hoist; and in certain details of construction, combination and arrangement of parts, all as I will proceed now more particularly to set forth and finally claim.

35 In the accompanying drawings, illustrating the invention, in the several figures of which, like parts are similarly designated, Figure 1 is a diagrammatic or plan view of a portion of a warehouse equipped with the invention. Fig. 2 is a plan view, on a larger scale, showing a portion of the framework 40 of a building, and illustrating one method of suspending the overhead tracks and the swinging crane from the ceiling girders or roof chords of said framework. Fig. 3 is 45 a transverse section, taken substantially in the plane of line 3—3, Fig. 2, and looking in the direction of the arrows. Fig. 4 is an elevation of a portion of a warehouse 50 or other structure, with its wall broken away, and showing another manner of supporting or pivoting the swinging crane, and Fig. 5 is an enlarged detail view of the arrangements shown in Fig. 4 showing the 55 manner of suspending the circular tracks from the girders, and also the manner of

supporting and guiding the radially extending traveling crane, upon the tracks, and the manner of supporting or pivoting the inner end thereof.

60 In the drawings the invention is illustrated as installed in a warehouse, and as shown in Fig. 1, the warehouse is located between a railroad track 1 and a dock 2, there being a railroad track 3 between the dock 2 and the warehouse.

4 is the end wall and 5 and 6 the front and rear walls of the warehouse, and 7 and 8 the front and rear platforms thereof.

70 The front and rear walls 5 and 6 of the warehouse are provided with a series of aligned doors or openings 9 and 10, respectively, and arranged within the warehouse and suspended from the ceiling thereof, is a circular track 11 of a diameter to fit the 75 width of the warehouse, and located on a central line between the doors 9 and 10. Concentrically within the circular track 11 there is fixed a smaller circular track 12, and mounted upon these circular tracks is 80 a swinging crane or girder 13, pivoted at its center 14 so as to swing about said tracks from the center to different positions in the warehouse as indicated in dotted lines. Supported at the doors 9 and 10 in line with the 85 swinging crane 13 and extending outside of the building to a position overhanging the track 1 at the rear of the building and to the edge of the dock 2 at the front of the building, are fixed short girder sections or 90 I-beams 15 and 16, respectively, and suitably supported upon the frame work within the warehouse and projecting from the corners and center of the end wall thereof and extending radially of the central track 11 95 and to the periphery thereof, are other short sections of I-beams or girders 17.

The parts above described comprise what might be called a single unit of the invention, and in the installation of the invention 100 in a warehouse, as many of such units as the length of the warehouse will accommodate are placed therein, the circular tracks of the successive units being placed in close juxtaposition to provide for coöperation between 105 the adjacent units in conveying material from one unit to another throughout the series of units. In Fig. 1 I have shown one complete unit and a portion of another unit, to illustrate this feature of the invention.

110 In Fig. 1 short stationary sections of I-beams or girders 18 are fixed to the frame-

work of the building above small doors or other openings 19 in the front and rear walls, and diverge radially to the peripheries of the circular tracks 11 of the adjacent units of the conveyer system.

As shown in Figs. 2 and 3 the circular tracks are secured to the girders or roof chords 20 of a warehouse or other structure, as by means of any suitable clips or fastenings, as at 21, Fig. 3. As shown in said Fig. 3, the swinging crane 13 is supported upon the circular tracks 11 and 12 by means of roller brackets 22 and 23, respectively, secured to the upper side of the crane arm 13, and in order to provide a central pivot or bearing for the crane arm, a pin or bolt 24 is suspended from a truss 25 fixed to and supported upon the girders 20 above the central circular track 12 and engages an opening in a plate 26 fixed to the upper side of the crane arm 13.

As shown in Figs. 4 and 5 the swinging crane arm 13 is pivoted or supported upon a post 26' fixed to the floor of the building 25 in alignment with the front and rear doors of the building, the crane arm being pivoted to the upper end of the post by a roller or ball bearing 27 as shown in Fig. 5, or in any other suitable manner.

As shown in Fig. 5, the short stationary sections of I-beams or girders 15 and 16 may be secured to the circular track 11 at their inner ends, and at their outer ends to brackets 28 fastened to the wall of the building.

The pivoted or swinging crane member 13 is preferably constructed of a section of I-beam or girder, and in accordance with this invention any suitable form of standard hand or electric driven hoist 29 is mounted 40 to travel upon the lower flanges of the crane arm by means of a roller carriage 30, and the position of said hoist may be changed by the rotary or swinging movement of the crane to cover any desired angle or position within the circumference of the circular track or its working area, either by hand or by any suitable or desired mechanical devices.

As above stated, a single unit comprehends one entire circular track section which may be constituted of one or more swinging cranes or girders from a single radial point, or they may be continuous and fixed at a radial point or center to cover complete diameter operations or travel at the hoist, the former arrangement being illustrated in Figs. 1, 4, and 5, and the latter arrangement being illustrated in Figs. 2 and 3.

The operation of the apparatus of system is as follows: To unload a box-car 31 located at the door 10 on track 1, and place or stack the articles in either of the left hand corners of the warehouse or at intermediate points, the hoist 29 is moved out upon the short fixed girder 15 to receive the articles

from the car and then returned to the swinging crane 13 over girder 15 and then the load swung to any desired position, such as to either of the short fixed girders 17 and the articles conveniently piled or stacked in the corners and center of the warehouse, as shown in Figs. 1 and 4. Or, the hoist after receiving its load from the box-car, then may be caused to travel straight through the warehouse over the entire diameter of the circular track 11 and over the fixed extension girder 16, and the load delivered at the end thereof to be placed or stored upon the vessel 32.

By routing the hoist with its attached load from car 31 by swinging the crane to point 33 where the circular tracks 11 of the two adjacent units meet, and transferring the hoist from the crane 13 of the first unit to the crane of the next adjacent unit, the load may be swung to the door 9 of that unit and out upon the extension girder 16 of that unit to a point for ready delivery to the vessel 34; or continuing the hoist and its attached load from the point 33 straight through the diameter of the circular track of the second unit and so on, the load may be routed over the entire length of the warehouse to any other unit throughout the successive units and delivered to any desired point therein for storage and stacking, or for delivering the load at any desired point outside of the warehouse for loading cars or vessels at different points within the bounds of the front and rear 95 of the warehouse.

It will be understood that the invention is not limited to the exact details of construction herein shown and described, as the same may be altered in various particulars and still be within the scope of the claims herein.

Furthermore, the entire system may be suspended from the bottom chords of roof structures and knee braced to side columns, 110 or it may be supported on an independent framework from the floor foundation of a warehouse or other structure.

What I claim is:

1. An overhead radial conveyer system, 115 comprising a framework, a circular track suspended from the upper part of said framework, and a radially extending swinging hoist-supporting crane suspended from said track.

2. An overhead radial conveyer system, comprising a framework, a circular track suspended from the upper part of said framework, a radially extending swinging hoist-supporting crane suspended from said track, and roller brackets secured to said crane and engaging said track to movably support said crane upon said track.

3. An overhead radial conveyer system, 130 comprising a framework, a circular track

suspended from the upper part of said framework, a radially extending swinging crane suspended from said track, roller brackets secured to the crane and engaging 5 said track to movably support said crane upon said track, and a hoist movably suspended from said crane.

4. An overhead radial conveyer system, comprising a framework, a circular track 10 suspended from the upper part of said framework, a radially extending swinging crane suspended from said track, a central pivot or support for the inner end of said crane, roller brackets secured to the crane 15 and engaging said track to movably support said crane upon said track, and a hoist movably suspended from said crane.

5. An overhead radial conveyer system, comprising a framework, concentric circular 20 tracks of different diameters suspended from the upper members of said framework, a radially extending swinging crane suspended from said tracks, a central pivot or support for said crane, roller brackets secured to the 25 crane and engaging said tracks to movably support the crane upon said tracks, and a hoist movably suspended from said crane.

6. An overhead radial conveyer system, comprising a framework, a circular track 30 suspended from the upper members of said framework, a radially extending swinging frame suspended from said track, and fixed girders extending radially from the periphery of said track in alinement with said 35 crane, and a hoist movably suspended from said crane and adapted to be transferred from said crane to and from said fixed extension girders when the crane is moved into alinement with said extension girders.

7. In an overhead radial conveyer system 40 for warehouses and like buildings, a circular track suspended from the ceiling girders of said warehouses, a radially extending swinging crane suspended from said track, and a hoist movably suspended from said crane, 45 said crane adapted to be swung about the center of said track to convey a load carried by said hoist to any point within the radius or diameter of said track within said warehouse.

8. In an overhead, radial conveyer system 50 for warehouses and like buildings, a circular track suspended from the ceiling girders of said warehouse and of a diameter substantially equal to the width thereof, a radially extending swinging crane suspended from said track, a series of fixed girders extending radially from the periphery of said track in

alinement with said crane and to the corners and walls of said warehouse, and a hoist 60 movably suspended from the crane and adapted to be transferred from said crane to and from said fixed extension girders, said crane adapted to be swung about the center of said track to convey a load carried 65 by said hoist to any point within the radius or diameter of said track and also to points beyond the periphery of said track when the crane is brought into alinement with said fixed girders.

9. In an overhead conveyer system for warehouses and like buildings, a series of juxtaposed circular tracks suspended from the ceiling of said warehouse, fixed radial girders extending from the peripheries of 70 said tracks and projecting to the corners and walls of said warehouse and beyond the walls thereof through openings therein, radially extending swinging cranes suspended from each of said tracks and adapted to be 75 brought into alinement with said fixed extension girders, and a hoist movably suspended from each of said cranes, the said cranes adapted to be swung about the center of said tracks to convey a load carried there- 80 by to any point within the radius or diameter of said tracks and also to points beyond the peripheries thereof when the cranes are brought into alinement with said fixed extension girders, the meeting points of said 85 circular tracks affording coöperation between adjacent cranes, whereby the load carried by a single hoist may be transferred from one crane to the other and delivered at any point throughout the entire series of 90 95 conveyer units.

10. In an overhead radial conveyer system for warehouses and like structures, comprising a series of successive conveyer units, each comprising a circular track suspended from 100 the upper members of the framework of said structure, a radially extending swinging crane suspended from each of said tracks, and a hoist movably suspended from each of said cranes, the said tracks being arranged 105 in close proximity to each other at their peripheries to afford coöperation between the cranes of adjacent units, whereby the load carried by the hoist on one of said cranes may be transferred from one conveyer unit 110 to the other throughout the series of units and delivered to any point within the radius or area of any one of said units.

In testimony whereof I have hereunto set my hand this 27th day of November, 1920.

FREDERICK WOHN.
